WALTER C. ROSS, OF SPRINGFIELD, MASSACHUSETTS, ASSIGNOR TO BUXTON, INCORPORATED, A CORPORATION OF MASSACHUSETTS.

KEY CASE.

Application filed February 2, 1924. Serial No. 690,165.

This invention relates to key cases and, more particularly, to improvements in the mounting of the key retaining elements thereof.

5 The invention is particularly concerned with a mounting of the key retaining elements on their supporting means in a conveniently detachable manner. As customarily made, the key retaining elements are 10 first completely formed and afterwards laid in place in a partially formed plate which is afterwards bent into its final form and, when so bent, retains the elements in a more or less permanent fashion. The present invention 15 enables the plate and key retaining elements to be formed completely and later assembled. Likewise, the construction enables any desired hook to be detached at will.

Various solutions of this same general 20 problem have been provided heretofore, as I am aware, but in all which have come to my attention, there is the inherent disadvantage that the key retaining elements, although attachable and detachable with comparative ease, are prone to become detached from the case unintentionally at undesired times. For example, one solution for the problem is to provide an enlargement in the slot in which the key retaining element 25 swings, such enlargement being designed to permit free passage of the enlarged head of the key retaining element into and out of the socket in which it is pivotally supported. To restrain the elements from becoming accidentally detached from their 30 sockets, the enlargements referred to, have been located so as to be normally closed by the leather folder, forming the case. However, such a closure for the enlargement is 35 yieldable at best and, as the case becomes worn by service, the closure becomes less and less reliable and keys can escape or be pulled out at undesired times.

The object of this invention is to provide 40 in a key case improved means for detachably connecting the key retaining elements to their supporting means, characterized by the prevention of accidental detachment of the key retaining elements under any ordinary 45 conditions of service.

More particularly, it is an object of the invention to provide a detachable mounting for the key retaining elements, such that the latter need to be manipulated in a certain

manner, which could hardly occur accidentally, in order to detach them.

In carrying out my invention, use is made of the usual slot in which the key retaining element swings but the slot is closed at both ends and at no point allows the enlarged head of the element to pass therethrough. Instead of an enlargement in the slot, a separate entrance to the supporting socket for the head is provided and this entrance is made large enough to permit free passage of the head but not the body of the key retaining element. A cross bar, forming a closure for one end of the slot, is provided adjacent said entrance and the key retaining elements cannot be detached or attached without so manipulating them that the cross bar first enters and later leaves the key retaining loops of said elements.

Other objects and advantages will appear in the following description and in the illustrative embodiment of the invention in the accompanying drawings, in which:—

Fig. 1 is a front elevational view of an open key case embodying the invention;

Fig. 2 is a fragmentary perspective view, 80 taken from the rear, of the supporting plate for the key retaining elements;

Fig. 3 is a similar view showing a modification in the construction of the supporting plate;

Figs. 4, 5 and 6 are enlarged cross sectional views illustrating successive steps in the operation of detaching a key retaining element;

Figs. 7 and 8 are enlarged fragmentary 90 rear elevational and cross sectional views, respectively, of another modification in the construction of the supporting plate; and

Figs. 9 and 10 are front and side elevational views, respectively, of the enlarged 95 swivel head of one of the key retaining elements.

Referring to these drawings, the key case chosen to illustrate the invention is of the usual, well known type comprising a folder 100 of leather or other suitable material, the end portions 11 of which constitute flaps foldable in overlapping relation over the central portion 12, constituting the back of the case. Suitable means, such as the interengageable 105 fasteners 13, are provided to hold the flaps together in enclosing relation over the keys. The key retaining elements 14 are shown as

swivelled in, as well as pivotally supported from, a hollow cylindrical member 15, formed by rolling up the upper edge of a plate 16, which is suitably secured, as by 5 rivets 17, to the back 12. Any other suitable form of key case may be used, as desired, and that shown is chosen as an illustrative example of one suitable and representative type.

10 The key retaining elements may be constructed in any desired manner to afford a key retaining loop 17' and an enlarged head for reception in the socket afforded by the hollow cylindrical member 15. While it is 15 not necessary according to all features of this invention that the key retaining elements, or hooks, have a swivelled engagement in their sockets, I have chosen this form as being a commonly accepted and desirable one in the trade and as showing a broader application of the invention. For such mounting of the hooks each is provided with the equivalent of a ball head, which may be constructed as shown in Figs. 9 20 and 10 or in any other suitable manner. As there shown, the upper end of the shank of hook 14 is bent to form an approximately circular eye 18 and the extremity 19 of the shank, forming the closure of eye 18, is flattened somewhat as it is bent in order to form lateral offsets 20, one on each side of shank 14. The head, thus formed, is disposed within member 15 and the shank of the hook emerges therefrom through the usual transverse slot 21 provided therein. The offsets 20 form shoulders which engage the side walls of slot 21 and prevent passage of the head therethrough, when positioned as in Fig. 9. Obviously, the eye 18 functions 25 in a similar manner when the hook is turned, as in Fig. 10. It will be readily apparent that the wire from which the hook is made can be of uniform width throughout and does not need to be necked down adjacent 30 the head, as heretofore. While the head thus described is intended to swivel in its socket, it will be readily apparent to those skilled in the art that the head need not necessarily 35 swivel and can merely function as a trunnion for pure swinging movement.

40 While the socket for head 18 is shown as a transversely-slotted, hollow, cylindrical member, as frequently used in the trade, the invention, in all its aspects, is not restricted thereto and may be practiced with any other suitable form of socket having the characteristic features of the invention, as hereinafter pointed out.

45 According to this invention, each slot 21 is closed, or substantially closed, in the sense that the hook cannot escape therefrom except in the special manner hereinafter disclosed. The plate 16 forms a closure for the slots 21 at one end in the usual manner and 50 at the other end a cross bar 22 is provided.

The slots 21, while shown of uniform width, need not necessarily be uniform but they are so constructed that at all locations the heads 18 cannot pass therethrough. The slots 21, however, freely receive the widest portions 70 of the hooks other than their heads and permit the hooks to swing freely into and out of the case and to swivel, all in the usual manner.

To enable the enlarged head of each hook 75 to pass into or out of the socket afforded by member 15, an entrance opening of sufficient area is provided but this opening has no connection with slot 21 and is separated therefrom by the cross bar 22, or its equivalent. This opening, which is preferably located at the back of the member 15 so as to be normally concealed by the flexible back 80 12, may take the form of a slot 23 (Fig. 2) common to all the key retaining elements. Individual entrance openings, such as 24, may, however, be provided for each key retaining element, as shown in Fig. 3, the intervening portions such as 25 being bent 85 tangentially to member 15 to lie substantially in the plane of the body of plate 16. The particular location of the cross bars 22 may be varied within limits, as desired. The limits of variation are the desired angular extent of slots 21, which usually are at least 90 180 degrees in extent in order to permit the desired range of swinging movement of the key retaining elements. The location of the cross bar shown in Figs. 4 to 6 is well adapted for all practical purposes but a still lower location of it may be used, as shown in Fig. 8. The arrangement there shown requires that the hooks 14 be positioned nearly vertically in order to be attached or detached and where the most difficult detachment is desired, this arrangement is preferable.

In the practical use of the invention, both the plate 16 and the hooks 14 may be completely formed prior to assembly. To assemble a hook on plate 16, the plate and hook are positioned relatively to one another as illustrated in full lines in Fig. 6. The hook, or plate, is then moved so that the former occupies the position shown by dotted lines in Fig. 6 and, in order to assume this position, the cross bar must enter the retaining loop 17', passing through the spring closure thereof. A straight line pull on the hook suffices to snap it over bar 22 and into the dotted line position. The position of the hook 14 is then reversed, end for end, bringing the hook and plate into the relative positions shown in Fig. 5, with head 18 in position for entrance into opening 23. Another pull on the hook will cause it to be snapped over cross bar 22 and as the latter leaves the loop 17' both sides of the loop-forming portion of the hook are lodged in slot 21 and head 18 enters into its socket and assumes 105 110 115 120 125 130

the position shown in Fig. 4. To detach the hook, the described operations are reversed.

The assembly described is, of course, usually made prior to the fastening of plate 16

5 in the flexible case but it may be made afterward, whenever it is desired to remove a hook, because the flexible back 12 will yield, or can be so arranged as to yield, sufficiently for the purpose.

10 It will be noted that the hook in order to become detached must work its way over cross bar 22 in such a manner that the latter not only enters loop 17' but also subsequently leaves it and that it is extremely unlikely 15 that this can be accomplished accidentally. Consequently, for all practical purposes, the hooks, although detachable, are prevented from accidental detachment.

15 The invention has been disclosed herein, 20 in an embodiment at present preferred, for illustrative purposes but the scope of the invention is defined by the appended claims rather than by the foregoing description.

What I claim is:—

25 1. In a key case, a key retaining member, including a relatively large body portion having a key retaining loop, a relatively narrow shank and an enlargement on the shank forming a head by means of which 30 said member is supported for swinging movement, said head being smaller than said body portion, supporting means for said member affording a socket to receive said head and an entrance to said socket large 35 enough to permit said head but not the body of said member to freely enter the socket, said means having a slot therein to receive a portion of said shank and afford freedom 40 for the swinging movement of said member, the side walls of said slot being so spaced as to restrain passage of said head therethrough, said supporting means having means for obstructing both ends of said slot 45 sufficient to prevent said shank from passing out of the same, the obstructing means at one end of said slot disposed adjacent said entrance, said member being removable from said supporting means only by a relative

manipulation of the two which will cause 50 said last named obstructing means to enter and afterwards leave said key retaining loop.

2. In a key case, a key retaining hook having an enlarged head, means affording a 55 socket to receive said head and an entrance to the socket large enough to permit free entrance of the head but not the body of the hook, a closed slot provided in said means through which a part of said hook extends, 60 the walls of said slot at all parts thereof restraining passage of said head therethrough, and a cross bar forming one closure of said slot, said hook being removable by a relative manipulation of it and said means which 65 will cause the cross bar to enter and afterwards leave the key retaining loop of said hook.

3. In a key case, a suitable folder, a plate 70 mounted thereon and having one edge bent forwardly and rolled into substantially cylindrical form with the free end disposed substantially in the plane of the body of the plate, a substantially transverse slot provided in said cylindrical portion, a member having a key retaining loop and an enlarged 75 head to lie within said cylindrical portion and support the member for swinging movement in the confines of said slot, said head being too large to pass through said slot, 80 said plate having means for obstructing both ends of said slot sufficiently to prevent said member from passing out at the ends thereof, an opening provided between the obstructing means at one end of said slot and the body of the plate sufficient to permit said 85 head to pass into or out of said cylindrical portion, said opening being normally closed by said folder, said key retaining element being removable from said slot only by a manipulation of the same relatively to said 90 last named obstructing means which will cause the latter to first enter and later leave the key retaining loop of said member.

In testimony whereof I have affixed my signature.

WALTER C. ROSS.
